UNITED STATES PATENT OFFICE.

CARL ROTH, OF ZEHLENDORF, NEAR BERLIN, GERMANY.

TURBINE.

No. 902,252.

Specification of Letters Patent.

Patented Oct. 27, 1908.

Application filed June 24, 1908. Serial No. 440,182.

To all whom it may concern:

Be it known that I, CARL ROTH, a citizen of the Confederation of Switzerland, and resident of 9 Annastrasse, Zehlendorf, near Berlin, German Empire, have invented certain new and useful Improvements in Combined Pressure and Velocity Flow Turbines, of which the following is an exact specification.

10 This invention relates to mixed turbines of the kind in which the first expansion stage takes place in a velocity flow turbine and the later expansion stages take place in pressure flow turbines. In such turbines when the 15 stages are arranged co-axially the velocity stage is made of larger diameter than the first pressure flow stage. It is also usual in turbines to arrange the pressure flow stages on parts of the drum of different diameters. 20 In such turbines employing pressure flow stages the end balancing by means of a single dummy piston or balancing surface arranged at the step from the velocity flow turbine to the first stage of the pressure flow 25 turbine has not proved to be efficient under all conditions of loading. Thus if the conditions are arranged for full loading with condensation of the exhaust steam then should the load be diminished or should the 30 turbine work with ordinary exhaust into the atmosphere, the balancing effect is to a great extent lost. In order to avoid these difficulties the present invention relates to a construction of balancing means for such mixed 35 turbines, in which a plurality of the dummy pistons or balancing surfaces are employed one for each of the diameters of the pressure flow part, the first dummy piston being the 40 annular surface formed at the step between the velocity flow turbine and the first diameter of the pressure flow turbine.

The invention is illustrated in the accompanying drawings in a diagrammatical manner.

45 Figure 1 is a section diagrammatically illustrating one arrangement of turbine according to the present invention, Fig. 2 illustrates a modified arrangement.

According to the form shown in Fig. 1 50 steam enters by the pipe *a* and passes through the velocity flow turbine *b*, the partially expanded steam then passes to those stages of the pressure flow turbine which are arranged on the first diameter *c*. At the 55 step from the diameter of the velocity flow turbine *b* to the turbine stages *c* there is ar-

ranged an annular dummy piston surface *k*. It will be seen that the velocity flow stage *b* is between the labyrinth packing *h* and the dummy piston *g*. The steam after passing 60 through the pressure flow stages *c* reaches the chamber *l* and then passes through the pressure flow stages *d* arranged on a part of the drum of larger diameter than the stages *c*. The stages *d* communicate with the exhaust *n*.

In Fig. 1 at the high pressure end of the turbine there is arranged a dummy piston formed by the annular surface between the parts of the diameters marked *e* and *f* on the drawing. The chamber *l* in front of this dummy piston is placed in communication with the chamber *k* by means of a pipe *m*. The center of the drum is placed in communication with the exhaust pipe *n* and the space *l* is in a fluid-tight manner separated from the interior of the drum by means of labyrinth packing *i*.

It will be seen that the dummy piston *g* is subjected to the pressure of partially expanded steam and this dummy piston is sufficient to counteract the unbalanced end pressures occurring in the stages *c*. The dummy piston surface between the diameters *e* and *f* is arranged to balance the unbalanced end pressures in the stages *d*. By this arrangement the regulation of the end balancing pressure proceeds in an exceedingly automatic manner, without the employment of a complicated mechanism employing the end movement of the turbine shaft.

According to the form of this invention shown in Fig. 2 the packing *h'* is arranged as described with reference to the packing *h* in Fig. 1 as also is the dummy piston surface *g'*. The space *h'* between the stages *c'* and *d'* is placed in communication with the center of the drum by means of an opening *o*, the packing *i'* is arranged at the low pressure end of the turbine. In this form the surface marked *D* in Fig. 2 forms the second balancing surface or dummy piston for those stages of the turbine which are arranged on the part of the drum of larger diameter.

The operation of this device proceeds in substantially the same automatic manner as described with reference to Fig. 1. The diameter *f* in Fig. 1 however is substantially the average diameter of the pressure flow parts *d*.

I claim:

1. In a mixed turbine having a high pres-

sure velocity flow stage and a plurality of pressure flow stages arranged co-axially in series therewith on parts of the drum of different diameter, the diameter of the first 5 pressure flow stage being less than that of the velocity flow stage, end balancing means for the pressure flow parts comprising separate dummy pistons for each of the diameters of said pressure flow parts, the dummy piston 10 surface for the first pressure flow stages being the step in the diameter from the velocity flow turbine to the diameter on which said stages are arranged, and a labyrinth packing arranged before the velocity 15 flow part.

2. In a mixed turbine having a high pressure velocity flow stage and a plurality of pressure flow stages arranged co-axially in series therewith on parts of the drum of different diameter, the diameter of the first 20 pressure flow stage being less than that of the velocity flow stage, end balancing means for the pressure flow parts comprising separate dummy pistons for each of the diameters of said pressure flow parts, the dummy piston 25 surface for the first pressure flow stages being the step in the diameter from the velocity flow turbine to the diameter on which said stages are arranged, and a labyrinth 30 packing arranged before the velocity flow parts, said packing being subjected on its low pressure side to the pressure at the step from the diameter of the first pressure flow

stages to the diameter on which the second set of pressure flow stages are arranged.

3. In a mixed turbine having a high pressure velocity flow stage and a plurality of pressure flow stages arranged co-axially in series therewith on parts of the drum of different diameter, the diameter of the first 40 pressure flow stage being less than that of the velocity flow stage, end balancing means for the pressure flow parts comprising separate dummy pistons for each of the diameters of said pressure flow parts, the dummy piston surface for the first pressure flow stages being the step in the diameter from the velocity flow turbines to the diameter on which said stages are arranged, and a labyrinth packing arranged before the velocity flow 45 part, said packing being subjected on its low pressure side to the pressure at the step from the diameter of the first pressure flow stages to the diameter on which the second set of pressure flow stages are arranged, a further 50 packing arranged also at the high pressure end of the turbine and adapted to preserve the pressure difference between the said intermediate pressure and the exhaust.

In witness whereof I have hereunto set my 55 hand in the presence of two witnesses.

CARL ROTH.
